(57) CLAIM

The ornamental design for a athletic face mask, as shown and described.

DESCRIPTION

FIG. 1 is a front perspective view of a first embodiment of the athletic face mask.

FIG. 2 is a left side view thereof.

FIG. 3 is a right side view thereof.

FIG. 4 is a top view thereof.

FIG. 5 is a bottom view thereof.

FIG. 6 is a front perspective view of a second embodiment of the athletic face mask.

FIG. 7 is a left side view thereof.

FIG. 8 is a right side view thereof.

FIG. 9 is a top view thereof; and,

FIG. 10 is a bottom view thereof.

The broken lines do not form part of the claimed design.
